US0D1024037S

(12) **United States Design Patent** (10) **Patent No.:** **US D1,024,037 S**
(45) **Date of Patent:** **** Apr. 23, 2024**

(54) **HOUSING FOR MOBILE PHONE**

(71) Applicant: **Ergonomic Solutions International Limited**, Surrey (GB)
(72) Inventor: **Benny Burmester**, Norresundby (DK)
(73) Assignee: **ERGONOMIC SOLUTIONS INTERNATIONAL LIMITED**, Surrey (GB)

(**) Term: **15 Years**

(21) Appl. No.: **29/712,564**

(22) Filed: **Nov. 8, 2019**
Related U.S. Application Data

(62) Division of application No. 35/505,478, filed on Jun. 21, 2018 (U.S. filing date under 35 U.S.C. 384), and having an international filing date of Jun. 21, 2018, now abandoned.

(30) **Foreign Application Priority Data**

(57) **CLAIM**

The ornamental design for a housing for mobile phone, as shown as described.

DESCRIPTION

FIG. 1 is a top plan view of the housing for mobile phone; FIG. 2 is a bottom plan view of the housing for mobile phone;

FIG. 3 is an end view of the housing for mobile phone; FIG. 4 is a left side view of the housing for mobile phone; FIG. 5 is right side view of the housing for mobile phone; FIG. 6 is an opposite end view of the housing for mobile phone; and,

FIG. 7 is a perspective view of the housing for mobile phone.

The broken lines, and unshaded surfaces bound or adjacent to broken lines, are included for the purpose of illustrating portions of the housing for mobile phone that form no part of the claimed design.

1 Claim, 7 Drawing Sheets
